W. V. HUKILL.
TELESCOPIC SIGHT.
APPLICATION FILED MAY 8, 1913.

Patented Jan. 20, 1914.

O.R. 350-249

UNITED STATES PATENT OFFICE.

WILLIAM V. HUKILL, OF BETHANY, WEST VIRGINIA.

TELESCOPIC SIGHT.

1,085,048.

Specification of Letters Patent.

Patented Jan. 20, 1914.

Application filed May 8, 1913. Serial No. 766,282.

To all whom it may concern:

Be it known that I, WILLIAM V. HUKILL, a citizen of the United States, and a resident of Bethany, in the county of Brooke 5 and State of West Virginia, have invented a new and Improved Telescopic Sight, of which the following is a full, clear, and exact description.

The invention relates to Galilean telescopes and its object is to provide a new 10 and improved sight for such telescopes to permit the use of the Galilean telescope on surveying instruments, rifles and other devices for sighting purposes.

15 In order to accomplish the desired result use is made of cross wires and a diaphragm, of which the cross wires are associated with the concave eye-piece of the telescope and the diaphragm is associated with the objective of the telescope, and the said diaphragm is provided with an opening and with slots 20 whereby a field is obtained having a bright portion due to the opening and dimmed portions due to the slots and in which the side 25 portions of the cross wires are visible when using the telescope while the central portion of the cross wires is not visible on the bright portion of the field.

A practical embodiment of the invention 30 is represented in the accompanying drawings forming a part of this specification, in which similar characters of reference indicate corresponding parts in all the views.

Figure 1 is a perspective view of a transit 35 telescope, provided with the improved sight; Fig. 2 is a longitudinal central section of the same; Fig. 3 is a view of the field of observation with the target in the center of the field; Fig. 4 is a similar view of the 40 same with the targets appearing at the upper and lower portions of the field; and Fig. 5 is a similar view of the same with the targets appearing at the sides of the field.

45 The Galilean telescope shown in Figs. 1 and 2 is provided with the usual tube A in which is mounted the objective B and the concave eye-piece C. A sighting wire D is associated with the eye-piece C and the 50 sighting wire may be in the form of a single

wire extending diametrically of the eye-piece C, or in the form of cross wires, the sighting wire being secured in position by suitable attaching means E held on the tube A, the sight wires extending through slots 55 in the tube of the eye-piece C in case the eye-piece is the movable part.

A diaphragm F is associated with the objective B, preferably by mounting such diaphragm in the outer end of the tube A and 60 fastening the same by a screw G to a plug G', as indicated in Fig. 2. The diaphragm F is provided with a central opening F', which may be square, as shown in Fig. 1, and the diaphragm is also provided with 65 horizontal slots F² and vertical slots F³ in alignment with the sighting wires D. The slots F², F³ preferably extend from the peripheral edge of the diaphragm F to within a short distance of the corresponding walls 70 of the opening F', as plainly indicated in Fig. 1, so that when the telescope is used for sighting purposes then the field of observation H shown in Figs. 3, 4 and 5 discloses a central bright portion H' due to the 75 opening F' and dimmer portions H² due to the slots F², F³, the dimmer portions H² appearing half round with the centers at the inner ends of the slots F², F³, that is, in close proximity to the corresponding 80 edges of the brighter central portions H'.

It is well known that in a Galilean telescope as heretofore constructed cross wires cannot be used for sighting purposes but by providing a diaphragm with the slots 85 F², F³ the side portions of the cross wires D appear as black bands or stripes D' in the said dimmed portions H², while the central parts of the cross wires D are not visible in the bright central portion H'. The line 90 of sight pierces the point at the center of the field where the stripes would meet if projected. By the observer moving the eye horizontally and vertically across the eye-piece C the ends of all the stripes may be 95 made to touch this point one at a time.

It is understood that by having the central bright portion wholly unobstructed by the cross wires the target appears to the 100 fullest advantage in the field H, and it is

well known that the cross wires in ordinary surveying instruments are sometimes in the way when doing certain work.

By reference to Figs. 3, 4 and 5, it will be noticed that the image of a target I is in different positions, that is, it may be viewed in central or in upper or lower positions when sighting for alinement or measuring a hori-angle, or it may be made to appear to the right or left when leveling or measuring a vertical angle. This is accomplished by the observer moving the eye across the eye-piece C in a corresponding direction while the telescope is clamped in position.

In Fig. 3 the target I is shown with its center in line with both horizontal and vertical sight bands D', its center coinciding with the line of collimation. In order to make sure that the center of the target I is in the vertical sight plane the end of either one of the vertical sight bands D' may be brought in contact with it as indicated in Fig. 4 by the observer moving the eye up or down in line with the vertical sight bands D'. In this case the horizontal sight bands D' disappear. In order to test the position relative to the horizontal sight plane the observer moves the eye along the horizontal sight bands D' until the end of one of the horizontal sight bands is brought to the target I as shown in Fig. 5. In this case the vertical sight bands disappear. It will be noticed that by the peculiarity just described the accuracy of the sight compares favorably with that of the telescope sights now generally used.

When using the telescope on guns or rifles in taking aim, the target is brought in line with all the sight bands D', as shown in Fig. 3.

The diaphragm F is provided with a slot F⁴ for the passage of the screw G so as to allow of properly adjusting the diaphragm F with a view to move the slots F² and F³ in accurate register with the cross wires D. The slots F² and F³ terminate a distance from the walls of the opening F' so as to avoid glimmering in the field opposite the sight stripes or bands D'.

It will be noticed that by the arrangement described the Galilean telescope, that is, one with a concave eye-piece, can be used for sighting purposes, and as such telescope is very short it is well adapted for use on portable surveying instruments, rifles and other devices. The telescope is short owing to the distance between the objective and the eye-piece being the difference between their focal length instead of their sum as is the case in a telescope having a convex eye-piece. A concave eye-piece gives a brighter field because it absorbs less light on account of using but a single lens instead of a series of

spaced lenses as is the case in terrestrial eyepieces. The field has less color and distortion because it is less affected by chromatic and spherical aberration and hence the telescope gives a better definition, which is an important factor in a surveying instrument or in a gun sight.

The telescope sight shown and described is simple, cheap in construction and accurate, and is free from parallax. The sight is adjusted for distance without interfering with the line of collimation. It is well known that in a common telescope the line of collimation is determined by the cross wires and the center of the objective, and the latter is to be moved to adjust for distance, and to insure this adjustment without disturbing the line of collimation, a costly construction is required. Moreover, there is always parallax unless the adjustment for distance is made with care. In the arrangement described, the line of collimation is determined by the cross wires and the slots of the diaphragm, and neither of these need be moved to adjust the telescope to different distances. The adjustment may be made by moving either the eye-piece or the objective, and there is no parallax even if an adjustment is not carefully made, or if it is not made at all, it being understood that the adjustment is left to be made by the eye, as it generally is to some extent. A telescope of low power with a long and small tube such as are used for hunting gun sights, may be made with non-acromatic lenses thus providing the advantage owing to the fact that acromatic lenses are spoiled by dampness while the others are not.

Although the sighting wires D are shown and described as attached to the tube A and the diaphragm F is illustrated and described in front of the objective B, such constructions may be varied without departing from the spirit of my invention, which consists essentially in providing a Galilean telescope with a sighting device, the cross wires of which are associated with the concave eye-piece and the diaphragm is associated with the objective either in the front or the rear thereof.

Having thus described my invention, I claim as new and desire to secure by Letters Patent:

1. A Galilean telescope provided with a sight attachment comprising a sighting wire and a diaphragm, the sighting wire being associated with the concave eye-piece of the telescope and the diaphragm being associated with the objective of the telescope, the diaphragm having an opening and slots and the said sighting wire being in alinement with the said slots.

2. A Galilean telescope provided with a sight attachment comprising a sighting wire

and a diaphragm, the sighting wire being associated with the concave eye-piece of the telescope, and the diaphragm being associated with the objective of the telescope, the 5 diaphragm having an opening and horizontal and vertical slots, the inner end of each slot terminating a distance from the wall of the said opening and the said sighting

wire being in alinement with the said slots.

In testimony whereof I have signed my 10 name to this specification in the presence of two subscribing witnesses.

WILLIAM V. HUKILL.
